SPOOL

Hilyard C. Howsam, Chicago, Ill., assignor to
Hubbard Spool Company, Chicago, Ill., a corpo-
ration of Illinois

Application October 2, 1937, Serial No. 166,966

2 Claims. (Cl. 242—123)

My invention relates to spools adapted particularly for heavier service, as for example for supporting wire.

The object of the invention is to produce a strong and rigid but comparatively light spool formed of simple sheet metal parts accurately fitted and secured together so that the operation of the spool during winding of wire thereon or unwinding of wire therefrom is balanced.

My improved spool and its construction are shown on the accompanying drawing, in which:

Figure 1 is an end view of the spool; and

Figure 2 is a section on plane II—II of Figure 1.

The barrel 10 of the spool is preferably of a length of seamless tubing of metal such as steel, and the heads 11 are in the form of annular plates of steel each provided with a central opening 12 whose inner diameter is the same as the inner diameter of the barrel 10, the heads abutting the ends of the barrel.

At each end of the spool is a supporting and aligning structure in the form of a sheet metal plate 13 whose central portion is deflected inwardly to provide a hub comprising the cylindrical wall 14 and the inner wall 15. The outer diameter of the cylindrical wall 14 is such that the hub part will fit the opening 12 of the heads 11 and the adjacent end of the barrel 10, so that the walls 14 will serve to center the heads 11 relative to the barrel and form supports for the barrel ends, the outer portions of the plates 13 engaging against the outer faces of the heads to hold the heads against the ends of the barrel, the structure 13 being secured in place as by welding thereof to the heads and to the barrel.

Extending axially through the barrel 10 is the arbor receiving tube 16 which is preferably a length of seamless steel tubing. The inner walls 15 of the structure 13 have openings 17 for receiving the ends of the arbor tube, and preferably portions of the walls 15 are deflected outwardly to provide flanges 18 to surround and seat the arbor tube and to which the tube may be secured as by spot welding. The structures 13 will thus accurately and securely hold the arbor tube and the barrel in concentric relationship and against relative axial displacement.

At each end of the spool is an end plate 19 of sheet metal secured against the corresponding head by deflecting the peripheral portion 11' of the head around the peripheral portion of the plate. The outer walls of the structures 13 are of less diameter than the end plates 19, and to receive the outer walls of the structures 13 the inner portions 19' of the end plates are deflected

outwardly to clamp against the structures 13 when the outer portions 11' of the heads are clamped around the peripheral portions of the end plates. The end plates have central openings 20, and the portions X of the walls 19' surrounding these openings are deflected inwardly and against the inner faces of the walls 19' to form double thickness walls surrounding the openings 20 to strengthen the end plates. The diameter of the openings 20 is substantially the same as the inner diameter of the arbor tube 16, and the arbor tube ends 16' outside of the supporting flanges 18 are flared as shown, so that they may abut against the flat inner sides of the deflected over end portions X of the walls 19' surrounding the openings 20 and so that when the end plates 19 are secured by deflecting over of the head peripheral portions 11', the end plates will be intimately held against the outer ends of the arbor tube. The deflected over portions X of the end plates present rounded surfaces Y around the openings 20 to facilitate insertion of supporting arbors through the openings, and the flared ends 16' of the arbor tube 16 will facilitate easy entrance of the arbor structure into the arbor tube for support of the spool during the winding or unwinding operations.

The end plate walls 19' are provided with openings 21 in alignment with openings 22 in the inner walls 15 of the supporting structure 13, these openings serving to receive drive pins, and serving also for venting the interior of the spool. In addition to the deflected over peripheral portions 11' of the heads 11, the end walls may be secured as by spot welding at points where the end walls engage the supporting structures 13, as indicated at Z.

I thus produce a strong and rigid yet comparatively light all sheet metal spool of few parts accurately aligned and secured together to form a balanced structure which will turn accurately during the process of winding wire thereon or unwinding wire therefrom. I do not desire to be limited to the exact construction and arrangement shown and described, as changes and modifications may be made without departing from the scope and spirit of the invention.

I claim as follows:

1. A spool comprising a tubular sheet metal barrel, heads in the form of sheet metal disks abutting the ends of said barrel and having openings in register with the barrel bore, end frames formed integral of sheet metal and each frame comprising a cylindrical hub portion and inwardly and outwardly extending radial flanges at the inner and outer ends thereof respectively, the hub

- portion of each end frame extending through the opening of the respective head disk and into the adjacent end of the barrel bore, the outwardly extending flange of each end frame being comparatively short and intimately engaging against the outer face of the respective head disk, the hub portions of said end frames being intimately secured to the barrel for intimately clamping the head disks between the barrel ends and the outwardly extending flanges of the end frames, end plates engaging against the outer faces of said end frames and having their outer peripheral portions deflected inwardly for intimate engagement with the outer portions of the head disks, said end plates and the outwardly extending flanges of said end frames and said head disks being intimately secured together by welding, the outer peripheral portions of said head disks being deflected around the peripheral edges of said end plates, the inwardly directed flanges of said end frames having aligned openings, an arbor receiving tube extending through said openings, said end plates having openings in register with said arbor tube.
2. A spool comprising a tubular sheet metal barrel, heads in the form of sheet metal disks abutting the ends of said barrel and having openings in register with the barrel bore, end frames formed integral of sheet metal and each frame comprising a cylindrical hub portion and inwardly and outwardly extending radial flanges at the inner and outer ends thereof respectively, the hub
- portion of each end frame extending through the opening of the respective head disk and into the adjacent end of the barrel bore, the outwardly extending flange of each end frame being comparatively short and intimately engaging against the outer face of the respective head disk, the hub portions of said end frames being intimately secured to the barrel for intimately clamping the head disks between the barrel ends and the outwardly extending flanges of the end frames, end plates engaging against the outer faces of said end frames and having their outer peripheral portions deflected inwardly for intimate engagement with the outer portions of the head disks, said end plates and the outwardly extending flanges of said end frames and said head disks being intimately secured together by welding, the outer peripheral portions of said head disks being deflected around the peripheral edges of said end plates, the inwardly directed flanges of said end frames having aligned openings, an arbor receiving tube extending through said openings, said end plates having openings in register with said arbor tube, the portions of said end plates surrounding the end plate openings being deflected inwardly and radially outwardly to form a double wall with a curved edge surrounding the end plate opening, the ends of said arbor tube being flared outwardly and abutting against the deflected portions of the end plates.
